DESIGN FOR A MAILBOX

Anthony J. Batzler, Milwaukee, Wis.

Application May 13, 1947, Serial No. 139,020

Term of patent 14 years

(Cl. D74—9)

To all whom it may concern:

Be it known that I, Anthony J. Batzler, a citizen of the United States, residing at Milwaukee, in the county of Milwaukee and State of Wisconsin, have invented a new, original, and ornamental Design for Mail Boxes, of which the following is a specification, reference being had to the accompanying drawing, forming a part thereof.

I claim:

The ornamental design for a mail box, as shown.

ANTHONY J. BATZLER.
